TILE

Hugh Sheldon Wiley, 53 Palmer Ave., Bronxville, N.Y.

Filed Oct. 17, 1958, Ser. No. 53,021

Term of patent 3½ years

(Cl. D18—2)

FIG. 1

FIG. 2

Fig. 1 is a top plan view of a tile, showing my new design; and

Fig. 2 is an edge view thereof.

The design for the tile disclosed is characterized by the arcuate band separating a conventional terrazzo pattern from a plain area within the area, said band having a raised metallic strip embedded therein, all as shown.

I claim:

The ornamental design for a tile, as shown and described.
